UNITED STATES PATENT OFFICE.

HENRY H. COPPOCK AND FRANK W. MILLER, OF PLEASANT HILL, OHIO.

CHURN.

SPECIFICATION forming part of Letters Patent No. 599,598, dated February 22, 1898.

Application filed April 20, 1897. Serial No. 632,944. (No model.)

To all whom it may concern:

Be it known that we, HENRY H. COPPOCK and FRANK W. MILLER, of Pleasant Hill, in the county of Miami and State of Ohio, have 5 invented a new and Improved Churn, of which the following is a full, clear, and exact description.

This invention is a churn having a body or cream-receptacle with a horizontal rotary 10 dasher-shaft. The parts have certain features of construction and relative arrangement by which a more effective structure is produced.

This specification is the disclosure of one 15 form of our invention, while the claim defines the actual scope of the conception.

Reference is to be had to the accompanying drawings, forming a part of this specification, in which similar characters of reference indicate corresponding parts in all the figures.

Figure 1 is a sectional view of the invention on the line 1 1 of Fig. 2. Fig. 2 is a sectional view of the invention on the line 2 2 of Fig. 1, and Fig. 3 is a detail section on the line 3 3 of 25 Fig. 1.

The body is supported on legs 4 and has a bottom 5 with four perpendicular sides 6, forming a square structure. The top 7 has a glass-covered observation-opening 8 and an 30 inwardly-extending cleat 9, running into the body. Two opposite sides of the body have their upper edges located slightly above the upper edges of the remaining two sides, so as to be engaged by the top 8 and hold the same, 35 as indicated in Fig. 1, thus leaving a space 10 between the top and the said remaining sides, through which air may circulate into the churn during the churning operation. The portions of the cleat 9 which are adjacent to 40 the spaces 10 are separated from the inner walls of the body, so as to leave spaces 11, forming continuations of the spaces 10.

The dasher-shaft 12 is held within the body parallel with the spaces 10 and 11, so that the 45 revolution of the shaft will create a current of air passing through one space 10 and the companion space 11 into the churn-body and out of the same through the remaining spaces 10 and 11. Fixed to the shaft 12 are a series of radial arms 13, respectively carrying 50 dasher-blocks 14. Each block 14 has a diag-

onally-beveled front portion *a* and a concave rear face *b*. The blocks 14 are arranged out of line on the shaft 12, and the beveled portion *a* of each block throws the cream laterally against the following block, which causes a thorough agitation of the cream. The concave rear faces *b* of the blocks cause a vacuum behind each block, which draws the cream into the vacuum and further facilitates the 60 thorough agitation of the cream.

One end of the shaft 12 is supported by a thumb-screw 15, operating in a bearing 16 and having its inner end seated in a concavity in a cap 17, secured on the said end of the 65 shaft 12. The opposite end of the shaft has a cap 18 with a square hole 19, receiving the squared inner end of a shaft 20, which is revolvably mounted in the body and carries a pinion 21. The shaft 20 is held by a block 22, 70 secured to the outer side of the body and having a stub-shaft 23, on which an internal spur-gear 24 is revolvably mounted. The gear 24 has a handle 25, whereby the gear may be driven, and the gear 24 meshes with the gear 75 21 to turn the shaft 20 and consequently the shaft 12.

The bottom 5 of the body is formed of a solid block, with its upper face inclined downward and inward from each side edge that is 80 parallel with the shaft 12, so that the block 26 has a longitudinal valley *c* formed on each side by two diversely-inclined surfaces *e* and *f*. This construction causes the interior of the churn to dry very quickly when the churn 85 has been washed and also makes an undulating surface over which the cream may roll and on which the cream will be more effectively treated.

Having thus described our invention, we 90 claim as new and desire to secure by Letters Patent—

In a churn, the combination of the four-sided body having the upper edges of two opposite sides higher than the upper edges of 95 the other two sides, one of said latter sides having a recess on its inner face at its upper edge, a cover resting on the higher edges, a cleat secured to the under face of said cover and extending down into the body, said cleat 100 being spaced from the sides of said body, whereby air-spaces are formed, but extending

beyond the inner surface of the recessed side into the said recess, a shaft mounted to rotate in said body, dasher-blocks carried by said shaft, said blocks having a concaved rear face and a beveled front face, and gearing adapted to rotate said shaft, the blocks being turned with their front faces toward the zigzag opening formed between the recessed side and the

cover and their concaved rear faces toward the opening between the opposite side and the cover, as and for the purpose set forth.

HENRY H. COPPOCK.
FRANK W. MILLER.
